CLAIM

The ornamental design for a laptop computer, as shown and described.

DESCRIPTION

FIG. 1 is a front, right side, perspective view of a laptop computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view in an open state;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a perspective view thereof shown with additional broken line environmental features forming no part of the claimed design.

The broken lines indicate portions of the article that form no part of the claimed design.

1 Claim, 9 Drawing Sheets
